UNITED STATES PATENT OFFICE.

MARTHA VIOLA BAUER, OF WASHINGTON, DISTRICT OF COLUMBIA.

REFRIGERATOR.

Application filed September 19, 1919. Serial No. 324,860.

To all whom it may concern:

Be it known that I, MARTHA VIOLA BAUER, a citizen of the United States, residing at Washington, District of Columbia, have invented certain new and useful Improvements in Refrigerators, of which the following is a specification.

This invention relates to improvements in refrigerators.

10 In ordinary refrigerator construction, a drain pipe is led from the ice compartment downwardly within the food compartment of the refrigerator at the rear thereof and extends at its lower end through the bottom of 15 the food compartment where it may discharge into a drip pan. These pans are frequently permitted to overflow through neglect, and when quite full their withdrawal from beneath the refrigerator is an inconvenient 20 and laborious task. It is a well recognized fact that notwithstanding the precautions taken, the drain pipe extending downwardly within the food compartment is an unsanitary arrangement.

25 One of the primary objects of the present invention is to construct a refrigerator in which the employment of the usual drain pipe through the food compartment is eliminated.

30 Another object of the present invention is to provide a refrigerator or ice chest in which the necessity for a drip pan is obviated.

35 A further object of the present invention is to construct a refrigerator or ice chest in which means are provided for disposing of the drippings in a sanitary and convenient manner, which means preclude all possibility of the drippings overflowing in case they 40 should be forgotten.

Another object of the present invention is to construct a refrigerator or ice chest provided with a drain receptacle in water-tight communication with the ice compartment 45 which receptacle is provided with removable means whereby the inner surface thereof is readily accessible for cleaning purposes.

A further object of the present invention is to construct a refrigerator which is provided with a drain receptacle located outside of the food and ice compartments, said drain receptacle having water-tight communication with the ice compartment.

The present invention accomplishes these 55 and other objects and provides a refriger-

ator or ice chest which can easily be kept in an absolutely sanitary condition throughout as every portion thereof is readily accessible for cleaning purposes.

In the accompanying drawings:

Figure 1 is a perspective view of a refrigerator constructed in accordance with the present invention;

Fig. 2 is a vertical front to rear section therethrough;

Fig. 3 is a rear elevation of the refrigerator.

In many respects the refrigerator or ice chest proper does not differ from the ordinary refrigerator, comprising a casing indicated in general by the numeral 1 and consisting of a front wall 2, side walls 3, a top 4, a bottom 5, and a back or rear wall 6. For a purpose to be presently explained, the side walls 3 and top 4 are extended rearwardly as indicated respectively by the numerals 7 and 8 so as to provide a housing 9 at the rear side of the refrigerator. The usual partition 10 divides the refrigerator into an upper ice compartment indicated in 80 general by the numeral 11, and a lower food compartment indicated in general by the numeral 12, the former opening through the top of the refrigerator and being adapted to be closed by a hinged lid 13, and the latter 85 opening through the front of the refrigerator and being adapted to be closed by a hinged door 14. The ice compartment is so lined and partitioned as to provide an ice receiving chamber indicated by the numeral 15 and water and milk tanks indicated 90 respectively by the numerals 16 and 17. The ice chamber 15 and the tanks 16 and 17 are provided respectively with hinged lids 18, 19 and 20. Faucets 21 and 22 are preferably 95 provided leading from the tanks 16 and 17 respectively, so that the contents of the tanks may be drawn off as desired.

The ice chamber 15 is provided with a downwardly and rearwardly inclined bottom indicated by the numeral 23, and a short drain pipe or conduit 24 leads from the rear of the ice chamber at the rear or lower side of the bottom 23 and through the rear wall 6 of the refrigerator casing, this 105 drain pipe being preferably inclined downwardly at a slight angle. A suitable strainer 25 is preferably provided at the intake or forward end of the pipe 24 so as to prevent the passage of solid particles from the ice 110

chamber into the said pipe. At its rear end the pipe communicates with the upper side of the drain receptacle which is indicated in general by the numeral 26. This receptacle is mounted upon the rear side of the rear wall 6 and is housed within the housing 9 heretofore referred to.

The drain receptacle comprises a flat or plane front wall 27 of substantially circular outline which wall rests flat against the rear face of the wall 6 as clearly shown in Fig. 2 of the drawings and may be provided with attaching ears 28 for the passage of screws or other securing elements 29 which serve to secure the drain receptacle to the said wall of the refrigerator casing. The opposite wall of the receptacle is outwardly bulged and is indicated by the numeral 30, this latter wall being convex and having a relatively large opening 31 formed therein, the wall of which opening is threaded to receive a similarly formed flange 32 at the periphery of a closure head 33 which is thus adapted to be removably fitted into position closing the opening 31. The closure head 33 may be provided with a marginal flange 34 to bear against a gasket 35 disposed against the edge of the wall 30 so as to provide a water-tight closure between the parts, and it is preferable that the said head be provided upon its outer side with projections 36 or any other suitable elements which may be conveniently grasped by hand, or which will permit of the application of a tool, for the purpose of removing and replacing the closure head. The drain receptacle is provided with this removable section in order that the interior of the receptacle may be readily accessible for cleaning purposes. In fact the head 33 constitutes the major portion of the rear wall of the said receptacle and as a result when the head is removed access may be had to all portions of the interior of the receptacle and even to the drain pipe or conduit 24 and a drainage outlet pipe which will now be described. This outlet pipe is indicated in general by the numeral 37 and the same has a flared or funnel end 38 which communicates with the interior of the receptacle 26 at the bottom thereof. The pipe 37 is led downwardly and laterally at a slight angle of inclination and through the extension 9 of one of the side walls of the refrigerator casing. The outer end of the pipe may be provided with a suitable faucet 39 by opening the valve of which water within the receptacle 26 may be drawn off as desired.

From the foregoing description of the invention it will be evident that water resulting from the melting of the ice within the ice chamber 15 will flow out through the drain pipe or conduit 24 into the drain

receptacle 26 where it will accumulate, the valve of the faucet 39 being closed.

It is preferable that the drain receptacle 26 be of a capacity to contain all of the water resulting from the melting of a quantity of ice sufficiently large to substantially fill the ice chamber 15. It is evident that even should the water be allowed to accumulate in the drain receptacle longer than usual, it cannot overflow, since the drain receptacle and the ice compartment with which it has water tight communication, form a continuous container and the water must necessarily rise in the ice chamber when the drain receptacle becomes filled.

Having thus explained the nature of my invention and described an operative manner of constructing and using the same, although without attempting to set forth all of the forms in which it may be made, or all of the positions in which it may be applied, what I claim as new is:—

1. In a refrigerator, an ice compartment, a food compartment, and a drain receptacle in water-tight receiving communication with the ice compartment and having one of its walls contiguous to one wall of the food compartment, another wall of the drain receptacle having a removable section whereby access may be had to the interior of said receptacle for cleaning the same.

2. In a refrigerator, an ice compartment, a food compartment, and a drain receptacle in receiving communication with the ice compartment and of substantially conoidal form, the plane wall of the said receptacle being contiguous to one wall of the food compartment, the curvilinear wall of the receptacle having an opening therein concentric thereto, and a closure head removably fitted in said opening.

3. In a refrigerator, an ice compartment, a food compartment, a drain receptacle having water tight communication with said ice compartment and located without both said compartments, and removable means whereby access may be had to the interior of said receptacle for cleaning the same.

4. In a refrigerator, a casing, an ice compartment within the casing, a drain receptacle upon the exterior of the casing, means establishing a water tight communication between the ice compartment and drain receptacle, and removable means whereby access may be had to the interior of said receptacle for cleaning the same.

5. The combination with a refrigerator having an ice compartment and a food compartment, of a receptacle located without both said compartments having water tight communication with said ice compartment and constituting with the ice compartment a continuous container for holding the water resulting from the melting of the ice, the said receptacle being provided with separate

openings for cleaning and draining the same, and means for normally closing the openings to prevent the escape of water.

6. In a refrigerator, a casing, an ice compartment within the casing, a drain receptacle upon the exterior of the casing, an outlet in said drain receptacle, a conduit leading from the ice compartment through a wall of the casing into the drain receptacle

establishing water tight communication between said ice compartment and drain receptacle, and a removable section in said drain receptacle whereby the same may be cleaned. 10

In testimony whereof I affix my signature. 15

MARTHA VIOLA BAUER. [L.S.]
